DESIGN FOR A NOISE MAKING TOY GUN

George L. Bumbaugh, Indianapolis, Ind.

Application March 12, 1943, Serial No. 109,743

Term of patent 7 years

To all whom it may concern:

Be it known that I, George L. Bumbaugh, a citizen of the United States, residing at 523 East Seventeenth Street, Indianapolis, in the county of Marion and State of Indiana, have invented a new, original, and ornamental Design for Noise Making Toy Guns, of which the following is a specification, reference being had to the accompanying drawing, forming a part thereof.

In the drawing Fig. 1 is a side elevational view of a noise making toy gun, showing my new design.

Fig. 2 is a top plan view thereof.

I claim:

The ornamental design for a noise making toy gun, as shown.

GEORGE L. BUMBAUGH.
